FLUID DISPENSING APPARATUS

Filed June 18, 1940

FIG. I.

FIG. II

INVENTOR:

VIRGIL D. BARKER,
William E. Paige,
Attorney.

UNITED STATES PATENT OFFICE

2,303,316

FLUID DISPENSING APPARATUS

Virgil D. Barker, Westfield, N. J.

Application June 18, 1940, Serial No. 341,121

10 Claims. (Cl. 221—73.5)

Although not limited to any particular embodiment, my invention may be advantageously embodied in apparatus for dispensing air at an automobile service station. At such a station, compressed air is principally used for operation of elevators to lift vehicles to permit them to be greased with facility; to dispense grease under pressure to the bearings of such vehicles, and to inflate the vehicle tires. It is ordinary practice to highly compress air, say to 150 pounds per square inch, by a pump operated by an electric motor, and to store it in a supply tank from which it may be released through dispensing apparatus which is adjustable to predetermine the pressure to which any air receiver may be charged.

Letters Patent of the United States No. 2,162,474 was granted June 13, 1939 to me for Fluid dispensing apparatus, of the class above contemplated and operative to dispense compressed air by a succession of pulsations until the back pressure through the dispensing conduit reaches that to which the controlling means is adjusted. That apparatus includes two control valves (shown in Fig. VI) each separately spring pressed toward its closed position but adapted to be automatically opened, by compressed air operating through lever linkages, to dispense the highly compressed air in such pulsations, through the dispensing conduit, until the selected pressure, variably predetermined by manual adjustment of a spring, is attained in the tire or other air receiver. In that patented structure, the two valves are operated in proper sequence by respective rocker cams, in cooperative relation with respective rocker cam levers, carrying respective rollers, which are independently spring stressed into cooperative relation with the rocker cams. It is the object and effect of my present invention to simplify the construction, arrangement, and method of operation of that patented structure. Both inventions utilize two diaphragm chambers each containing a pressure sensitive reciprocating diaphragm, subjected to stresses in opposite directions by fluid pressure and a spring opposed to such pressure, but, in said patent, the fluid in one of said chambers is continually in communication with the atmosphere through a restricted vent local to that chamber and remote from the valve casing in which said two valves are mounted, whereas, in the present invention, the only fluid vent to the atmosphere is unrestricted and in the valve casing containing both of said valves, and what is hereinafter termed the second of those valves positively controls the

escape of fluid to the atmosphere from the first diaphragm chamber by alternately opening and closing that unrestricted vent in the valve casing. Moreover, the present invention includes a restricted duct in the valve casing continually limiting the rate of flow of fluid to one of the diaphragm chambers.

Both of said diaphragms are intermittently subjected to the maximum fluid pressure directly from a supply reservoir or other source, but one is continually in communication with such source through said restricted duct, whereas the other diaphragm is continually subjected to fluid pressure from the air service conduit.

Moreover, in said patent both of the valves in the valve casing are arranged to be operated by respective rocker cams which are formed by levers of the first order, whereas, in the present invention, only one of the two valves, viz., the one hereinafter designated the first valve, which controls the admission of high pressure air from the supply to both the service conduit and the second diaphragm chamber, is arranged to be operated by a rocker cam, and that cam is formed by a lever of the second order. The other valve, hereinafter designated the second valve, is arranged to be directly operated to control the vent of fluid pressure to the atmosphere by a bell crank lever subjected to fluid pressure from the service conduit opposed by the adjustable spring, operated by the fluid, as a lever of the first order, to close that valve, and operated by the spring, as a lever of the second order, to open that valve.

My invention operates in positively controlled cycles to force successive pulsatory charges of fluid into a receiver; each charge of fluid being automatically terminated at an interval after its initiation.

Only a small quantity of the high pressure fluid from the source is required to furnish sufficient power for operating the apparatus, and it is subsequently exhausted to the atmosphere through said vent in the valve casing.

My invention comprises the various novel features of construction, arrangement, and method of operation hereinafter more definitely specified.

In the drawing, Fig. I is a rear elevation of a main casing, connected with a conduit leading from the high pressure fluid supply reservoir and with a fluid dispensing service conduit, and said casing encloses the two diaphragm chambers and has on the front thereof indicating mechanism, not

shown herein, including a plurality of adjustable numbered wheels.

Fig. II is a longitudinal sectional view of the valve casing shown in Fig. I and including the restricted vent connecting the two chambers in which the valves are respectively mounted, and also including the unrestricted vent to the atmosphere controlled by the second valve.

In said drawing, the main casing 1 encloses two diaphragm chambers 2 and 3, each containing a reciprocating diaphragm, respectively 4 and 5. The fluid pressure supply conduit 6, from any suitable source of highly compressed air, supplies such air to said diaphragm chambers under automatic valve control, as hereinafter described. The fluid pressure service conduit 8 leads from said chamber 3, and the compressed air is dispensed through it to the receiver. For the purpose of servicing and inflating automobile tires, said service conduit 8 may have a flexible dispensing hose 8' connected therewith having at the discharge end thereof a suitable connecting fitting or chuck 8'', of well known design, for convenient attachment to a tire valve stem 8''. Such a chuck embodies a valve which closes to prevent air from escaping from the hose when not attached to a tire stem, but is automatically opened and automatically unseats the tire valve when the chuck is properly applied to the tire valve stem. Rear cover 9 of casing 1 is partly omitted.

Said diaphragm 5, which is subjected to the fluid pressure in said service conduit 8, has operatively connected therewith the reciprocating plunger 5'. The bell crank lever 11, which is fulcrumed on the shaft 12, between a pair of suitable bearings 13 in said casing 1, has its short arm 11' in cooperative relation with said plunger 5' and has its long arm 11'' connected with the right hand end of the spring 15. The left hand end of said spring 15 carries the nut 16 which is in threaded engagement with the adjusting screw 17 cut on the shaft 18 extending exterior to said casing 1 and provided with the crank handle 19 by which it may be adjusted. That is to say, the stress of said spring 15 may be increased by turning said crank 19 clockwise or decreased by turning it counterclockwise.

I find it convenient to connect with said shaft 18 indicating means for manifesting in pounds the pressure to which the receiver is to be charged, which is predetermined by the manual adjustment of said spring 15. Such means includes a gear pinion 21 on said shaft 18 and the intermediate gear 22 which meshes with the indicator mechanism gear 26.

When the crank handle 19 is turned by the operator, the gear 26 turns the indicating mechanism which, as disclosed in detail in my Patent No. 2,162,474 aforesaid, includes three wheels each having on its circumference a series of numbers from "1" to "9" and "0". The first of said wheels, which indicates individual pounds, is connected, by tens-transfer gearing, with the second numbered wheel, each of the numbers on which represents tens of pounds, and that second wheel is connected, by tens-transfer gearing, with the third numbered wheel, each of the numbers on which represents hundreds of pounds. That arrangement is such that upon a complete rotation of the successive numbered wheels of lower order, the wheel of the next higher order is turned one-tenth of a revolution. Consequently, when the operator turns the crank handle 19, the three numbered wheels indicate the pounds pressure to which the apparatus is set by

the screw 17 stressing said spring 15 to move said bell crank lever 11. For instance, in the position shown, the screw 17 has been manually adjusted to insure dispensation of compressed air through the service conduit 8 until an automobile tire or other receiver is charged to a pressure of thirty-five pounds per square inch.

Said supply conduit 6 is connected with the valve casing 30 in communication with the valve chamber 31 therein, which is connected by the restricted air duct 32 with the valve chamber 33 having the passage 34 leading to the unrestricted vent 35 which opens through said casing 30 to the atmosphere.

15 Said valve chamber 33 is continually in communication with the fluid conduit 36 so that, when the passage 34 is closed, as shown in Fig. II and as hereinafter described, the high pressure air from the supply conduit 6 passes through the 20 restricted air duct 32 and said air conduit 36 into the chamber 2 beneath the diaphragm 4, stressing the latter upward. The passage 37 leads from the valve chamber 31 to the air conduit 38 which extends to the diaphragm chamber 3 25 beneath the diaphragm 5 and to the service conduit 8 through the T-fitting 38'. Therefore, when said passage 37 is open, the high pressure air is also supplied to the chamber 3 tending to uplift the diaphragm 5.

30 The first valve 40, which is mounted to reciprocate in said valve chamber 31, is continually stressed toward its closed position shown in Fig. II by its spring 41 tending to close said passage 37 leading to the air conduit 38. However, said 35 valve 40 is arranged to be opened by its stem 40' which extends through the stuffing box 42 on said valve casing 30 and is pivotally connected with the left hand end of the link 43, of which the right hand end is pivotally connected 40 with the rocker cam 44 which is a lever of the second order fulcrumed on the stud 45 fixed in said casing 1. The upper end of said rocker cam 44 has the right hand incline 44' engaged by the 45 roller 46 carried by the cam roller lever 47 and continually stressed into cooperative engagement with the rocker cam 44 by the spring 48 connecting the right hand end of said lever 47 with the stationary stud 49 fixed in the casing 1. The movement of said rocker cam 44 is limited by the stop studs 50 and 51 fixed in said casing 1 and, in the position shown, the roller 46 engaging the 50 rocker cam 44 has thrust the valve 40 open so that the high pressure air is passing from the supply conduit 6 into the diaphragm chamber 3 and the fluid service conduit 8, but the diaphragm 5 has not begun to move from its lowermost position shown in Fig. I in which it is held by the short arm 11' of the bell crank lever 11 under stress of the adjustable spring 15. In assembling the parts shown in Fig. I, the movement of the lever 11 by said spring 15 may be limited by the stationary stop stud 53 fixed in the casing 1. However, I provide the long arm 11'' of lever 11 with the adjustable set screw 54 and nut 54' to cooperate with stationary stop stud 55 fixed in casing 1, to adjustably limit the movement of said lever 11 by the spring 15.

The construction and arrangement above described are such that the high pressure air flowing into the diaphragm chamber 3 and service conduit 8 lifts the diaphragm 5 and turns the lever 11 clockwise against the stress of its spring 15 to close the passage 34 in the valve casing 30 by the valve 57, as shown in Fig. II, under stress of its spring 57'.

However, said valve is arranged to be opened by its rod 57', the right hand end of which is pivotally connected to the left hand end of the link 58, of which the right hand end is pivotally connected to the long arm 11'' of said lever 11. Fig. I shows the parts in the position in which the valve 57 is open to exhaust the air from the diaphragm chamber 2 beneath the diaphragm 4.

Said diaphragm 4, which is normally subjected to the high pressure fluid from the supply conduit 6 when the valve 57 is in the position shown in Fig. II, is relieved of that pressure when the valve 57 is open in the position of the parts shown in Fig. I, by the exhaust of the compressed air from the chamber 2 through the air conduit 36, casing 30, and the unrestricted vent 35 leading to the atmosphere, so that the diaphragm 4 then sinks to the position shown in Fig. I. Said diaphragm 4 has operatively connected therewith the reciprocating plunger 4'. The bell crank lever 60, which is fulcrumed on the shaft 61, between a pair of suitable bearings 62 in said casing 1, has its short arm 60' in cooperative relation with said plunger 4', and has its long arm 60'' connected with the left hand end of the spring 64. The right hand end of said spring 64 is anchored on said stud 55. Said cam roller lever 47 is fulcrumed on the pin 65 fixed in the long arm 60'' of said lever 60; so that the stress of said spring 64 has shifted the long arm 60'' against the stop lug 66 conveniently formed on the upper portion of the valve casing 30, as shown in Fig. I, and with the effect of placing the cam roller 46 in engagement with the right hand incline 44' of said cam 44 and thrusting the valve 40 to open position in which the high pressure air is admitted through the passage 37 to the fluid conduit 38 to lift the diaphragm 5 and charge the service conduit 8 with air at the high pressure from the source. However, as above noted, Fig. I shows the position of the parts with both valves open and immediately before the diaphragm 5 has been uplifted to turn the lever 11 clockwise at the initiation of a pulsation of pressure caused by reduction of pressure in the conduit 8 below that for which the spring 15 has been adjusted. That is also the position of the parts shown in Fig. I when the supply conduit 6 and service conduit 8 are disconnected respectively from the source of supply and the receiver to be charged.

When the supply conduit 6 is connected with a source of highly compressed air and the service conduit 8 closed at its discharge end by the chuck valve, or any other means, both the diaphragm chambers 2 and 3 are charged with the high pressure air, uplifting the diaphragms 4 and 5 and turning the bell crank levers 11 and 60 to the limit of their movement respectively clockwise and counterclockwise. Such movement of the lever 11 is limited by contact of its arm 11'' with the inner face of the right hand side wall of the casing 1. Such movement of the lever 60 is limited by the contact of the stop screw 67 which is axially adjustable in the arm 60'' of that lever and may be set in adjusted position by the nut 68 thereon. Said screw 67 encounters the inner face of the left hand wall of said casing 1. Such movement of the lever 60 causes the roller 46 to pass over the crest of the cam 44 into engagement with the left hand incline of said cam; so that the spring 48, tending to stress the right hand end of the lever 47 downwardly, causes the cam 44 to rock clockwise against the stop 51, withdrawing the valve rod

40' from the casing 30 and permitting the valve 40 to be closed by its spring 41. Such clockwise movement of the lever 11 causes the link 58 to withdraw the rod 57' of the valve 57 from the casing 30 and permits that valve to be closed by its spring 57''. It may be observed with reference to Fig. II that the valve rods 49' and 57' are each made in two sections in order to fit them into the valve casing 30, in view of the enlargements at both ends of said rods.

Both the supply conduit 6 and the service conduit 8 being charged with highly compressed air, and the stress of the spring 15 being adjusted to the pressure desired in a receiver, for instance a vehicle tire; connection of the chuck valve at the discharge end of the service conduit with the tire valve stem permits the high pressure air in the conduit 8 to escape into the tire until the pressure in the tire and in the service conduit is equalized, by decrement of the pressure in the conduit 8 and increment of the pressure in the tire. The decrement of pressure in the diaphragm chamber 3 beneath the diaphragm 5 permits the spring 15 to turn lever 11 counterclockwise with the effect of thrusting open the valve 57 by the link 58 and the rod 57' of that valve, thus permitting the escape of the high pressure air from the diaphragm chamber 2 beneath the diaphragm 4, through the air conduit 36, casing 30, and the unrestricted vent opening 35 in the valve casing 30. Such venting of the diaphragm chamber 2 permits the spring 64 to turn the lever 60 clockwise to the position shown in Fig. I, with the effect of forcing the roller 46 over the crest of the cam 44 to the right hand side thereof and permitting the spring 48 to rock the cam 44 counterclockwise to the position shown in Fig. I and thereby open the valve 40 to admit a pulsatory charge of highly compressed air to diaphragm chamber 3 and the service conduit 8. Such pulsatory charges are automatically effected in succession until the pressure in the tire or other receiver equals the pressure to which the spring 15 has been adjustably set. Thereupon, disconnection of the service conduit 8 from the tire permits the chuck valve to close and trap the highly compressed air from the source in the diaphragm chambers 2 and 3 and service conduit 8, ready for the initiation of another dispensing operation by permitting the highly compressed air to escape from the discharge end of the service conduit 8, as above described.

However, I do not desire to limit myself to the precise details of construction, arrangement, or method of operation herein set forth, as it is obvious that various modifications may be made therein without departing from the essential features of my invention, as defined in the appended claims.

I claim:

1. In fluid dispensing apparatus, the combination with a casing enclosing two diaphragm chambers, each containing pressure sensitive means including a reciprocating diaphragm; of a fluid pressure supply conduit through which fluid is supplied to said chambers; a valve casing including a constantly open restricted fluid duct connecting the supply conduit to the first chamber and a controlled vent to the atmosphere; a fluid pressure service conduit leading from the second chamber; respective springs opposed to the fluid pressure on said diaphragm; means for adjustably varying the pressure of the spring opposed to the diaphragm in the second cham-

ber; a first valve in said valve casing, controlling communication between the fluid pressure supply conduit and said second chamber; a second valve in said valve casing, controlling communication from said first chamber, through said controlled vent, to the atmosphere; means operatively connecting said second valve with the diaphragm in said second chamber and the spring opposed to that diaphragm; whereby said second valve is arranged to be closed by fluid pressure in the second chamber, and opened by the stress of the spring opposed to the diaphragm in said second chamber to vent the fluid pressure from the first chamber to the atmosphere; whereby upon reduction of fluid pressure in the second chamber below that for which the spring opposed thereto is adjusted, that spring opens said second valve, thereby exhausts the fluid pressure from the diaphragm in the first chamber and causes the first valve to be automatically opened, admitting the full fluid pressure from the source both to said service conduit and to the diaphragm in said second chamber, thereby first causing said second valve to be closed, and thereafter said first valve to be closed when the pressure in the first chamber, connected by the constantly open restricted duct to the supply conduit, overcomes the spring opposed to said first chamber diaphragm, until the fluid pressure in said second chamber is again reduced below that for which the spring opposed thereto is adjusted; whereupon the cycle of operation is repeated and said valves are automatically operated in accordance with fluctuations in the fluid pressure on both diaphragms and fluid is dispensed, in successive pulsations, from said supply conduit through said service conduit, until the pressure in the receiver is equal to the effective pressure of the adjusted spring; wherein the valves have respective springs continually stressing them toward their closed position, and means operatively connecting the first valve with the diaphragm in the first chamber and the spring opposed to that diaphragm including a bell crank lever, having a short arm in cooperative relation with that diaphragm and a long arm in cooperative relation with the latter spring, a rocker cam, a cam lever carrying a roller and pivoted at one end to said long arm, a spring continually stressing the cam lever with its roller in cooperative relation with the cam, and a valve push rod in operating relation with said rocker cam.

2. In fluid dispensing apparatus, the combination with a casing enclosing two diaphragm chambers, each containing pressure sensitive means including a reciprocating diaphragm; of a fluid pressure supply conduit through which fluid is supplied to said chambers; a valve casing including a constantly open restricted fluid duct connecting the supply conduit to the first chamber and a controlled vent to the atmosphere; a fluid pressure service conduit leading from the second chamber; respective springs opposed to the fluid pressure on said diaphragm; means for adjustably varying the pressure of the spring opposed to the diaphragm in the second chamber; a first valve in said valve casing, controlling communication between the fluid pressure supply conduit and said second chamber; a second valve in said valve casing, controlling communication from said first chamber, through said controlled vent, to the atmosphere; means operatively connecting said second valve with the diaphragm in said second chamber and the spring opposed to that diaphragm; whereby said second valve

is arranged to be closed by fluid pressure in the second chamber, and opened by the stress of the spring opposed to the diaphragm in said second chamber to vent the fluid pressure from the first chamber to the atmosphere; whereby upon reduction of fluid pressure in the second chamber below that for which the spring opposed thereto is adjusted, that spring opens said second valve, thereby exhausts the fluid pressure from the diaphragm in the first chamber and causes the first valve to be automatically opened, admitting the full fluid pressure from the source both to said service conduit and to the diaphragm in said second chamber, thereby first causing said second valve to be closed, and thereafter said first valve to be closed when the pressure in the first chamber, connected by the constantly open restricted duct to the supply conduit, overcomes the spring opposed to said first chamber diaphragm, until the fluid pressure in said second chamber is again reduced below that for which the spring opposed thereto is adjusted; whereupon the cycle of operation is repeated and said valves are automatically operated in accordance with fluctuations in the fluid pressure on both diaphragms and fluid is dispensed, in successive pulsations, from said supply conduit through said service conduit, until the pressure in the receiver is equal to the effective pressure of the adjusted spring; wherein the valves have respective springs continually stressing them toward their closed position, the means operatively connecting the second valve with the diaphragm in the second chamber and the spring opposed to that diaphragm includes a bell crank lever, having a short arm in cooperative relation with that diaphragm and a long arm in cooperative relation with the latter spring, and a valve push rod operatively connected to said long arm.

3. In fluid dispensing apparatus, the combination with a casing enclosing two diaphragm chambers, each containing pressure sensitive means including a reciprocating diaphragm; of a fluid pressure supply conduit through which fluid is supplied to said chambers; a valve casing including a constantly open restricted fluid duct connecting the supply conduit to the first chamber and a controlled vent to the atmosphere; a fluid pressure service conduit leading from the second chamber; respective springs opposed to the fluid pressure on said diaphragm; means for adjustably varying the pressure of the spring opposed to the diaphragm in the second chamber; a first valve in said valve casing, controlling communication between the fluid pressure supply conduit and said second chamber; a second valve in said valve casing, controlling communication from said first chamber, through said controlled vent, to the atmosphere; means operatively connecting said second valve with the diaphragm in said second chamber and the spring opposed to that diaphragm; whereby said second valve is arranged to be closed by fluid pressure in the second chamber, and opened by the stress of the spring opposed to the diaphragm in said second chamber to vent the fluid pressure from the first chamber to the atmosphere; whereby upon reduction of fluid pressure in the second chamber below that for which the spring opposed thereto is adjusted, that spring opens said second valve, thereby exhausts the fluid pressure from the diaphragm in the first chamber and causes the first valve to be automatically opened, admitting the full fluid pressure from the source both to said service conduit and to the diaphragm in said

second chamber, thereby first causing said second valve to be closed, and thereafter said first valve to be closed when the pressure in the first chamber, connected by the constantly open restricted duct to the supply conduit, overcomes the spring opposed to said first chamber diaphragm, until the fluid pressure in said second chamber is again reduced below that for which the spring opposed thereto is adjusted; whereupon the cycle of operation is repeated and said valves are automatically operated in accordance with fluctuations in the fluid pressure on both diaphragms and fluid is dispensed, in successive pulsations, from said supply conduit through said service conduit, until the pressure in the receiver is equal to the effective pressure of the adjusted spring; wherein the means operatively connecting the first valve with the diaphragm in the first chamber and the spring opposed to that diaphragm includes a bell crank lever, having a short arm in cooperative relation with that diaphragm and a long arm in cooperative relation with that spring, a rocker cam, a cam roller lever carrying a roller and pivoted at one end to said long arm, a spring continually stressing the cam roller lever with its roller in cooperative relation with the cam, and a valve push rod in operating relation with said rocker cam; the valves have respective springs continually stressing them toward their closed position, and the means operatively connecting the second valve with the diaphragm in the second chamber and the adjustable spring opposed to that diaphragm includes a bell crank lever, having a short arm in cooperative relation with that diaphragm and a long arm in cooperative relation with the latter spring, and a valve push rod operatively connected to said long arm.

4. In fluid dispensing apparatus, the combination with a casing enclosing two diaphragm chambers, each containing pressure sensitive means including a reciprocating diaphragm; of a fluid pressure supply conduit through which fluid is supplied to said chambers; a valve casing including a constantly open restricted fluid duct connecting the pressure supply conduit to a conduit leading to the first chamber and a controlled fluid vent to the atmosphere; a fluid pressure service conduit leading from the second chamber; respective springs opposed to the fluid pressure on said diaphragms; means for adjustably varying the pressure of the spring opposed to the diaphragm in the second chamber; a first valve in said valve casing, controlling communication between the fluid pressure supply conduit and said second chamber; a second valve in said valve casing controlling communication from said first chamber, through said casing vent, to the atmosphere; and means operatively connecting said first valve with the diaphragm in said first chamber and the spring opposed to that diaphragm, including a lever; whereby said first valve is arranged to be opened by the stress of the spring opposed to said first diaphragm and closed by fluid pressure on said first diaphragm; means operatively connecting said second valve with the diaphragm in said second chamber, including a lever; whereby said second valve is arranged to be closed by fluid pressure in said second chamber, and opened by the stress of the spring opposed to the diaphragm in said second chamber to vent the fluid pressure from the first chamber, through said valve casing, to the atmosphere.

5. In fluid dispensing apparatus, the combination with a casing enclosing two diaphragm

chambers, each containing pressure sensitive means including a reciprocating diaphragm; of a fluid pressure supply conduit through which fluid is supplied to said chambers; a valve casing including a constantly open restricted fluid duct connecting the pressure supply conduit to a conduit leading to the first chamber and a controlled fluid vent to the atmosphere; a fluid pressure service conduit leading from the second chamber; respective springs opposed to the fluid pressure on said diaphragms; means for adjustably varying the pressure of the spring opposed to the diaphragm in the second chamber; a first valve in said valve casing, controlling communication between the fluid pressure supply conduit and said second chamber; a second valve in said valve casing controlling communication from said first chamber, through said casing vent, to the atmosphere; means operatively connecting said first valve with the diaphragm in said first chamber and the spring opposed to that diaphragm, including a lever of the first order; whereby said first valve is arranged to be opened by the stress of the spring opposed to said first diaphragm and closed by fluid pressure on said first diaphragm; means operatively connecting said second valve with the diaphragm in said second chamber, including a lever of the first order; whereby said second valve is arranged to be closed by fluid pressure in said second chamber, and opened by the stress of the spring opposed to the diaphragm in said second chamber to vent the fluid pressure from the first chamber, through said valve casing, to the atmosphere.

6. In fluid dispensing apparatus, the combination with a casing enclosing two diaphragm chambers, each containing pressure sensitive means including a reciprocating diaphragm; of a fluid pressure supply conduit through which fluid is supplied to said chambers; a valve casing including a constantly open restricted fluid duct connecting the pressure supply conduit to a conduit leading to the first chamber and a controlled fluid vent to the atmosphere; a fluid pressure service conduit leading from the second chamber; respective springs opposed to the fluid pressure on said diaphragms; means for adjustably varying the pressure of the spring opposed to the diaphragm in the second chamber; a first valve in said valve casing, controlling communication between the fluid pressure supply conduit and said second chamber; a second valve in said valve casing controlling communication from said first chamber, through said casing vent, to the atmosphere; means operatively connecting said first valve with the diaphragm in said first chamber and the spring opposed to that diaphragm, including a bell crank lever; whereby said first valve is arranged to be opened by the stress of the spring opposed to said first diaphragm and closed by fluid pressure on said first diaphragm; means operatively connecting said second valve with the diaphragm in said second chamber, including a bell crank lever; whereby said second valve is arranged to be closed by fluid pressure in said second chamber, and opened by the stress of the spring opposed to the diaphragm in said second chamber to vent the fluid pressure from the first chamber, through said valve casing, to the atmosphere.

7. In fluid dispensing apparatus, the combination with a casing enclosing two diaphragm chambers, each containing pressure sensitive means including a reciprocating diaphragm; of a fluid pressure supply conduit through which

fluid is supplied to said chambers; a valve casing including a constantly open restricted fluid duct connecting said pressure supply conduit to a conduit leading to the first chamber and a controlled fluid vent to the atmosphere; a fluid pressure service conduit leading from the second chamber; respective springs opposed to the fluid pressure on said diaphragms; means for adjustably varying the pressure of the spring opposed to the diaphragm in the second chamber; a first valve in said valve casing, controlling communication between the fluid pressure supply conduit and said second chamber; a second valve in said valve casing controlling communication from said first chamber, through said casing vent, to the atmosphere; means operatively connecting said first valve with the diaphragm in said first chamber and the spring opposed to that diaphragm, including a lever of the first order, a lever of the second order forming a rocker cam, a cam lever carrying a roller, and a spring stressing said roller toward said cam, whereby said first valve is arranged to be opened by the stress of the spring opposed to said first diaphragm and closed by fluid pressure on said first diaphragm; 25

means operatively connecting said second valve with the diaphragm in said second chamber including a lever; whereby said second valve is arranged to be closed by fluid pressure in said second chamber, and opened by the stress of the spring opposed to the diaphragm in said second chamber to vent the fluid pressure from the first chamber, through said valve casing, to the atmosphere.

10 8. A structure as in claim 4, wherein the lever operatively connected to the spring opposed to the diaphragm in the first diaphragm chamber, carries means for adjustably varying the extent of its movement by that diaphragm.

15 9. A structure as in claim 4, wherein the lever operatively connected to the spring opposed to the diaphragm in the second chamber, carries means for adjustably varying the extent of its movement by that spring.

20 10. A structure as in claim 4, wherein each of the two levers respectively connected to the two springs opposed to the two diaphragms carries screw means for adjustably varying the extent of its movement.

VIRGIL D. BARKER.
